(57) **CLAIM**

The ornamental design for an alignment aid golf ball marker, as shown and described.

DESCRIPTION

FIG. 1 is a top view of the alignment aid golf ball marker;

FIG. 2 is a top perspective view of the alignment aid golf ball marker;

FIG. 3 is a bottom view of the alignment aid golf ball marker;

FIG. 4 is a left side view of the alignment aid golf ball marker;

FIG. 5 is a rear view of the alignment aid golf ball marker;

FIG. 6 is a front view of the alignment aid golf ball marker; and,

FIG. 7 is a top view of the alignment aid golf ball marker shown in relation to a golf ball.

The line on the top of the marker between the center of the curved edge and the point is part of the design. The right side of the alignment aid golf ball marker is a mirror image of the left side. The broken lines in FIG. 7 form no part of the design and are used to indicate a golf ball in an environment in which the golf ball marker may be used.
